UNITED STATES PATENT OFFICE.

DAVID L. KLINE AND MARTHA D. KLINE, OF NEWARK, NEW JERSEY.

WATER-HEATER.

No. 871,706.

Specification of Letters Patent.

Patented Nov. 19, 1907.

Application filed March 26, 1907. Serial No. 364,261.

To all whom it may concern:

Be it known that we, DAVID L. KLINE and MARTHA D. KLINE, citizens of the United States, residing at Newark, in the county of 5 Essex and State of New Jersey, have invented certain new and useful Improvements in Water-Heaters; and we do hereby declare the following to be a full, clear, and exact description of the invention, such as 10 will enable others skilled in the art to which it appertains to make and use the same, reference being had to the accompanying drawings, and to figures of reference marked thereon, which form a part of this specification. 15

This invention relates to a water heater, and is designed for places such as hotels, boarding houses, or similar situations where there is a constant demand for hot water, 20 and where the means for heating the water is confined to a range boiler.

This invention is designed to provide a heater that is installed around the flue pipe of a heating boiler for heating the house, and 25 another portion of the heater is installed in the flue of the chimney so that the heaters are subject to the heat coming from the house heater, either steam, hot water or hot air, and, a constant circulation is initiated by 30 means of the heating, and at the same time the withdrawal of water from the system in the house admits water that is compelled to pass through all the heating elements before it emerges, and in this way hot water 35 is constantly assured.

The invention is further designed to provide a heater, of this kind, that can be installed over any heater, and is preferably made of elements that are clamped or 40 secured together, and are thus in a position to be removed, when necessary, without unduly disturbing the heater or its flue connections.

In the drawings, Figure 1 is a side view of 45 the device showing the chimney in section. Fig. 2 is a vertical section of the heating elements showing the connection from one to the other. Fig. 3 is a section on line 3, in Fig. 1, and Fig. 4 is a view of a modified form 50 of construction.

Any form of heater 10 can be used in this device, and it is provided with the usual flue pipe 11 that leads into the chimney 12. Around the flue pipe, between the heater and 55 the chimney, is installed one of the heating

members comprising two chambers formed at one end to grasp and receive the flue pipe 11, and having the other end preferably abutting on the chimney and opening into the flue thereof. These chambers, of course, are hollow for the reception of water.

Arranged at approximately right angles thereto, and installed in the flue of the chimney, are the water chambers 15 and 16, the chamber nearest the heater being shortened so as to allow a passage for the products of combustion into the flue between the chambers, and thus into the chimney flue. These chambers are also hollow to receive water, and are preferably made semi-circular in cross-section so that when they are fitted together they can be fitted into the flue of the chimney. The longer of the pair of chambers, in the chimney, acts as a support by having its lower edge resting on a suitable base in the chimney flue. It will be understood that these halves or chambers of each of the heating members are provided with means so that the chambers can be fastened together to cause them to maintain their position. To connect the chambers with a supply system, a pipe 17 is installed having a suitable valve 18, and this pipe feeds into a pipe 19 which passes up between the chambers 15 and 16 in the flue between them, is thus subjected to heat, and then passes, by means of the return connection 20, into the chamber 16. The water is then passed through a pipe 21 into the chamber 14, from there it can be conducted, by the pipe 22, to a suitable coil or receptacle 23, installed in the heater. A pipe 24 is then used to convey the water into the heating chamber 13, and it then passes through the pipe 25 in the chamber 15, and then a return bend 26 is utilized to allow the water to flow out into the pipe 27 which passes down through the flue of the chimney, and is then conducted in any suitable direction to feed the piping system of the house that conducts hot water to where it is used.

This system is inexpensive to install, and has the advantage of being compact, and utilizes space, in a house, that is not usually used for anything, and also has the advantage of using up the heat coming from a heater, which at present is wasted and passes out the chimney without doing any good. The pipes 22 and 24, with the coil 23, can be dispensed with, if necessary, and a pipe 28 or 11

any other suitable element can be used to connect the chambers 13 and 14, this connection being shown in Fig. 2.

In Fig. 4 is illustrated a modified form of construction, where the pipe 17, conducting water to the heater, can be twisted into a coil 29 to envelop the flue pipe of a heater, the pipe then passing into a coil 30 which is installed in the flue of the chimney, and the pipe can then be led off, as at 31, to conduct hot water to any part of the house.

It will be understood, also, that the water chambers of the member inclosing the flue pipe, from the heater to the chimney flue, act as a sheathing to prevent overheating of the surroundings, because when a furnace is forced in severe weather, a flue pipe will sometimes become red hot and communicate the heat to surrounding wood-work, causing a fire. The present heater will prevent this.

Having thus described our invention, what we claim is:—

1. A heater comprising a pair of members arranged at an approximate right angle, each member consisting of separable chambers, one member arranged to embrace the flue pipe of a heater, the other member being installed in the flue of a chimney, and both members being arranged to form a flue through them, pipes connecting the chambers of the members, a pipe to conduct water to one of the members, and a pipe to conduct the water from the heater.

2. A heater comprising a pair of members arranged at an approximate right angle, each member consisting of a pair of chambers forming a flue between them, a pipe connecting each of the chambers of one of the members with a chamber of the second member, a pipe conducting water from one of the chambers of the second member through the heater, and returning to the other chamber of the second member, a pipe supplying water to the heater and passing

into one of the chambers of the first member, and a pipe passing from the other chamber of the first member to conduct water from the heater.

3. A water heater comprising a pair of members, one member consisting of a pair of chambers to form a flue between them, one of the chambers being longer than the other to form a support for the member and to permit the passage of gas into the flue between them, a second member comprising a pair of chambers to embrace the flue pipe of the heater, a pipe conducting water from each chamber of the first member to each of the chambers of the second member, a pipe conducting water to one of the chambers of the first member, a pipe conducting water from the other chamber of the first member, and a pipe connecting the chambers of the second member.

4. A water heater comprising a pair of members, one of the members comprising a pair of chambers to form a flue between them, a second member comprising a pair of chambers to embrace the flue pipe of a heater, one of the chambers of the first member being longer than the other to form a support for the member, and to permit the passage of gas into the flue between them, a pipe connecting each of the chambers of one member with one of the chambers of the other member, a pipe conducting water to one of the chambers of the first member, a pipe conducting water from the other chamber of the first member, and a pipe connecting the chambers of the second member.

In testimony that they claim the foregoing, they have hereunto set their hands this 23d day of March 1907.

DAVID L. KLINE.
MARTHA D. KLINE.
